FLORENT HINNEKENS, OF PATERSON, NEW JERSEY, ASSIGNOR TO VAN VLAANDEREN MACHINE COMPANY, OF PATERSON, NEW JERSEY, A CORPORATION OF NEW JERSEY

FINISHING MACHINE

Application filed November 12, 1928. Serial No. 318,885.

In machines for finishing fabrics of the class in which the goods in being passed lengthwise through the machine first undergo treatment with a sizing liquid and then are passed around a series of heated "cans" or drums to dry and set the size on the fabric it has heretofore been impossible to guard against the goods running at times on the bias, or so that the warp threads were not parallel with the longitudinal axis of the machine, or with a vertical plane perpendicular to the axes of the cans or drums, and also to prevent the piece running in varying width instead of at constant width. The consequence of course in any case is inferior goods, because the treatment leaves the goods permanently set with the faults therein. Of course the tendency of some goods to run faulty in the mentioned respects is greater than in others, but the tendency is always present however carefully the axes of the drums and other rotating elements may be set in order to have them absolutely parallel and although all such elements may be perfect cylinders. There is also to be taken into account the fact that the different pieces of goods to be treated have different widths.

In order to overcome these difficulties I provide a pair of transverse scales at each end of the machine (to wit, one forward of the sizing means and the other aft of the cans or drums) in which the scales in each pair are on opposite sides of a common plane at right angles to the axes of said drums and all the scales extend transversely of said plane and all have markings consecutively spaced from said plane and at equal intervals from each other and the markings on each scale have indices reading in regular progression from said plane, those on any one scale being identical to those on any other. Thereby the attendant or attendants have only to see that the side margins of the goods, as the run is being effected, coincide with the marking bearing the same index on all the scales. In consequence it is possible, without any special skill or effort on the part of the attendants, to produce finished goods which are free from the faults indicated and thus to avoid the great loss which is likely to be and hereto-

fore has frequently been an incident of the use of machines of this class.

I know of course that simple scales have been employed for use in directing work of divers kinds through machines for operating thereon: also, I recognize that it may possibly have been known to provide one such scale at the input and another at the output end of the machine. Such, however, would only serve where there had not to be taken into account the susceptibility, as in fabrics, especially when wetted with a size or other liquid, of the warp to become distorted or change in width during the progress through the machine. By providing two pair of scales, marked and indexed as stated, the attendants have means to assist them which not only serves as a guide for direction, and that as to each edge of the goods, but as a gage for width. If the goods, for instance, is thirty-four (34) inches wide, the attendants have only to see that each edge is initially made to coincide with the index 34 and keep it in such coincidence during the run.

When a fabric is woven some shrinkage almost invariably occurs in the weaving. Thus a piece of goods required to be thirty-four (34) inches, for example, will be actually less than thirty-four (34) inches when it leaves the loom. The weaving plant requires this discrepancy to be compensated for in the finishing. In order that this compensation may be effected in the use of my invention with certainty I preferably provide the pairs of scales on strips which are each adjustable lengthwise of their scales.

In the drawing:
 Fig. 1 is a plan of the improved machine;
 Fig. 2 a side elevation; and
 Figs. 3 and 4 details illustrative of the invention.

In a frame 1 are journaled with their axes parallel three "cans" or drums 2, two with their axes in one horizontal plane and the third below and with its axis in another horizontal plane, the drums being geared together by gearing 3 so that the two upper drums rotate in one direction and the lower drum in the opposite direction. The drums are as usual heated in some way, which is here im-

material. They are driven from a motor 4 through an endless chain 5 connecting a sprocket wheel 6 on the motor shaft with a sprocket wheel 7 and gearing 8 connecting the latter with the gear of one of the drums. 5 The receiving beam (not shown) is mounted at one end of the machine with one gudgeon in a bracket 9, slideable transversely of the machine on the bars 10, and with the other 10 gudgeon in a fork 11 (to which the beam is lashed in some way) revoluble in a bracket 12 upstanding from frame 1 and having splined thereon the gear 12 which meshes with a pinion 13 having a pulley 14 driven through a belt 15 from a pulley 16 rotating with sprocket wheel 7. The beam may occupy various 15 positions in a line transverse of the machine by shifting the bracket 9 and fork 11 lengthwise of the axis of the beam. The delivery beam (not shown), on which the goods to be treated comes to the machine, is journaled in bearing-brackets 17 at the other end of the machine frame. 18 is braking means to 20 preserve necessary tension on the beam and 19 generally denotes means for applying a sizing liquid to the sheet of goods before it passes the drums. This beam may also occupy various 25 positions in a line transverse of the machine by shifting brackets 17 on and lengthwise of bars 20. So much is well known.

On one bar (preferably the outer one) in each pair of bars 10 and 20 are placed two scales, those on the bar 10 being marked 10^a and those on the other bar 20^a. The scales in 30 each pair are marked off in inches or other equal linear units, and fractional portions of these units may also be marked off equally. The scale units and portions thereof of the pair of scales on one bar are equal to those of the other. Each scale has graduated indices, 35 as 30, 32, 34, etc. for its unit markings reading from the inner end of the scale. Further, the scales in one pair are respectively opposite, lengthwise of the machine, the scales in the 40 other pair, or so that viewing the two parts from one end of the machine the two right-hand scales read to the right from a vertical plane intermediate the scales of both pairs and the other two scales read to the left. Each 45 scale may be provided on a separate strip 21 attached to the bar 10 (20).

The objects being to have the width of the fabric adjacent one beam always the same as it is adjacent the other, so that in the finished 50 piece its width will not vary, and to insure the fabric as it passes through the machine being kept in a path truly perpendicular to the axes of the drums, so that it will not be in places skewed or distorted, it will be apparent that if the workman sees to it that both margins 55 register and continue in register with markings indexed alike (for instance, 34) on one pair of scales and also on the other these objects will be accomplished. The goods will in 60 consequence issue from the machine as free of

skewing or distorting, although finished and consequently more or less stiffened, as when they enter it, and but little skill on the part of the attendant or attendants is necessary to attain these results.

In order to afford compensation for shrinkage of the goods in the weaving or other previous treatment each strip 21 is adjustable on the bar 10 or 20 longitudinally of its scale, as by being provided with longitudinal slots 70 21^a to receive set screws 22 penetrating these slots and driven into the bar. The boss finisher sets the two strips apart a distance to compensate for the shrinkage; thus, if the goods have shrunk one-half of an inch and 75 are in fact thirty-four (34) inches wide instead of thirty-four and one-half (34 $\frac{1}{2}$) inches, he sets each pair of strips so that the distance between their markings 34 is actually 34 $\frac{1}{2}$ inches, and the attendant nevertheless 80 maintains the edges of the goods at the markings 34.

Having thus fully described my invention, what I claim is:

1. A finishing machine of the class in which 90 the goods are passed therethrough first in size-receiving relation to a size-applying means and then around the surfaces of a plurality of heated substantially cylindrical elements whose axes are parallel having two 95 pairs of scales arranged one relatively forward of said means and the other aft of said elements and with the scales in each pair on opposite sides of a common plane at right angles to said axes and all the scales extending 100 transversely of said plane and all having markings consecutively spaced from said plane and at equal intervals from each other and the markings on each scale having indices reading in regular progression from said plane and those on any one scale identical to those on any other scale.

2. A finishing machine of the class in which 110 the goods are passed therethrough first in size-receiving relation to a size-applying means and then around the surfaces of a plurality of heated substantially cylindrical elements whose axes are parallel comprising, with a frame supporting said means and elements, two pairs of strips arranged one relatively forward of said means and the other aft of said elements and all transversely of a plane cutting said axes at right angles thereto, the strips in each pair having scales on opposite sides of and transverse to said plane and all such scales provided with markings consecutively spaced from said plane and at equal intervals from each other and the markings on each scale having indices reading in regular progression from said plane and those on any one scale identical to those on any other, each strip being adjustable toward and from said plane.

In testimony whereof I affix my signature,

FLORENT HINNEKENS.
